(57) **CLAIM**

The ornamental design for a circuit breaker, as shown and described.

DESCRIPTION

FIG. 1 is a front view of a circuit breaker, showing our new design;

FIG. 2 is a rear view thereof;

FIG. 3 is a top view thereof;

FIG. 4 is a bottom view thereof;

FIG. 5 is a right side view thereof;

FIG. 6 is a left side view thereof; and,

FIG. 7 is a top, front and right side perspective view thereof.

The broken line portion of the figure drawings is included to show environment only and forms no part of the claimed design.
